Primary Examiner — John M Otte(74) *Attorney, Agent, or Firm* — JCIP Global Inc.(57) **CLAIM**

The ornamental design for a display screen with graphical user interface, as shown and described.

DESCRIPTION

FIG. 1 is a front view of a display screen showing a first image of a graphical user interface;

FIG. 2 is a front view of a display screen showing a second image of the graphical user interface;

FIG. 3 is a front view of a display screen showing a third image of the graphical user interface;

FIG. 4 is a front view of a display screen showing a fourth image of the graphical user interface;

FIG. 5 is a front view of a display screen showing a fifth image of the graphical user interface;

FIG. 6 is a front view of a display screen showing a sixth image of the graphical user interface;

FIG. 7 is a front view of a display screen showing a seventh image of the graphical user interface;

FIG. 8 is a front view of a display screen showing an eighth image of the graphical user interface;

FIG. 9 is a front view of a display screen showing a ninth image of the graphical user interface;

FIG. 10 is a front view of a display screen showing a tenth image of the graphical user interface;

FIG. 11 is a front view of a display screen showing an eleventh image of the graphical user interface;

FIG. 12 is a front view of a display screen showing a twelfth image of the graphical user interface;

FIG. 13 is a front view of a display screen showing a thirteenth image of the graphical user interface; and,

FIG. 14 is a front view of a display screen showing a fourteenth image of the graphical user interface.

The appearance of the graphical user interface of the display screen transitions between the images shown in FIGS. 1-14. The process or period in which the graphical user interface transitions forms no part of the claimed design. The dot-dash broken lines illustrate the display screen and form no part of the claimed design. The remaining broken lines illustrate portions of the graphical user interface that form no part of the claimed design.

Care Key Points

Pepper should be grown in full sunlight and kept away from standing water. It can be placed in a garden or in planters (though in the latter case it may need to be watered more often). Seedlings need about 24 inches of space between them. Pepper plants are annuals, which means they live for one year and then die. They produce small, round fruits that are typically red, yellow, or green when ripe. Peppers are a type of fruit that is often used in cooking. They are high in vitamin C and can be eaten raw or cooked. Pepper plants are relatively easy to grow and can be started from seed or purchased as seedlings. They require full sun and well-drained soil. Watering is important, but overwatering can lead to root rot. Pepper plants are susceptible to several pests and diseases, including aphids, caterpillars, and blight. These can be controlled with organic or chemical treatments. Pepper plants are also prone to powdery mildew, which can be treated with a fungicide. Pepper plants are a popular choice for home gardens because they are relatively easy to grow and produce a variety of fruits. They are also a good source of vitamins and minerals.
